FUZE SELF DESTRUCTION DELAY AND POINT DETONATION MECHANISM

Arthur S. Bennett, Rochester, N.Y., assignor, by mesne assignments, to the United States of America as represented by the Secretary of the Army

Filed Dec. 29, 1958, Ser. No. 783,629

3 Claims. (Cl. 102—86.2)

This invention relates to a fuze self-destruction delay and point detonation mechanism and more particularly to a novel means for releasing the firing pin in a fuze mechanism either upon target impact or by a self-destruction time delay mechanism.

The self-destruction mechanism of the invention is intended for use in a fuze of the type disclosed in a co-pending application filed May 27, 1955, Serial No. 511,807, now Patent No. 2,889,778, for Fuze Safety Device, wherein the firing pin of the fuze is held in a safe position by a wire connected to the nose cap of the fuze which is released to fire a detonator only upon fracture of the nose cap.

It is a primary object of this invention to provide a mechanism for the self-destruction of a projectile upon failure to strike a target after a predetermined time delay.

Another object is to provide a fuze for use with a projectile acting as a super-quick detonating device or as a self-destruction time delay mechanism for a projectile.

A further object is to provide a self-destruction and point detonation mechanism that is reliable and positive in action yet simple and economical in design.

The specific nature of the invention as well as other objects and advantages thereof, will be apparent from the following description of the preferred embodiment thereof as illustrated in the accompanying drawing, forming part of the specification, and in which like numerals are used to designate like parts throughout the same.

In the drawings:

Fig. 1 is a longitudinal fragmental sectional view taken through a fuze and illustrating somewhat schematically a point detonation and self destruction mechanism of the invention, the elements being in unarmed position,

Fig. 2 is a fragmentary section similar to Fig. 1 and showing the elements in point detonating position,

Fig. 3 is a fragmentary section similar to Fig. 2, the elements being in the self-destruction position, and,

Fig. 4 is an enlarged fragmentary section illustrating the firing pin and release member in the locked position of Fig. 1.

Referring now to the drawing, 1 indicates generally the mechanism of the invention housed in a fuze body 2 which is attached to a projectile (not shown). Fuze body 2 is provided with a nose cap 3 and is coaxially bored as at 4, 5, 6 and 7 to house the operating mechanism of the invention. Bore 7 houses a detonating charge 8 and a booster charge 9. Bore 6 receives a housing 10 which is bored as at 11 to receive a firing pin assembly designated generally by 12. The firing pin is slidably mounted in a bore 13 in the assembly and comprises a head 14, a firing point 15 and a stem 16. A coil spring 17 mounted in bore 13, normally biasing against head 14, urges pin 12 towards detonator 8. Stem 16 extends forwardly into a chamber, indicated generally by 18, formed in the forward portion of housing 10 and is provided with a notch 19 in its forward portion. The forward wall of notch 19 is beveled as best viewed in Fig. 4.

2

Releasable means to hold firing pin 12 in retracted safe position is provided and comprises a release member indicated generally by 20 and notched in its rearward portion as at 21 is connected at its forward end to a wire 22 which is attached as at 23 to a threaded member 22^a which is threadably engaged to nose cap 3. Notch 21 is similar to notch 19 and defines a beveled rearward wall. (See Fig. 4.)

As shown in Fig. 1, release member 20 is in its locked position and engaging firing pin 12. When in the aforesaid position, the beveled walls are mating at an angle of 20° to permit ready disengagement upon release of wire 22. Firing pin 12 and release member 20 are held in locked position by means of a lever 24 pivoted at one end as at 25, and a shorter lever 26 pivoted as at 27 to the other end of lever 24. Lever 26 is provided with a rounded nose 28 on its free end which is adapted to be received in a rounded notch 29 provided in release member 20 and in the locked position retains pin 12 and release 20 against a shoulder 30 formed by an insert 31 in chamber 18 and a shoulder 32 formed by housing 10. Pin 12 and release 20 therefore cannot separate unless lever 24 is rotated about pivot 25. Means for controlling lever 24 is provided and consists of a bar 33 which is pivotally attached to lever 24 at its free end and extends into bore 5 for operative connection to a self-destruction time delay mechanism which consists of a gear train indicated generally by 34 and which comprises gears 35, 36, 37, 38, 39 and 40 all being pivoted to suitable supporting 30 structure indicated by 41. Gear 40 is coaxially fixed to a ratchet wheel 42 which is operably connected to a pawl 43. Gear wheel 35 carries a coaxially fixed circular cam 44 having a circumferentially disposed notch 45 which is adapted to receive an integral lug 46 on the forward 35 end of bar 33. Lug 46 normally rides against the peripheral surface of cam 44. Bar 33 is provided with a notch 47 which is adapted to engage a locking tab 48 fixed to supporting structure 41. A spring 49 connected at one end to supporting structure 41 and bar 33 urges lug 46 against the peripheral surface of cam 44.

Gear wheel 35 and cam 44 are mounted for conjoint rotation on shaft 50 which is rotated by a suitable device such as a clock spring or the like (not shown).

Means for initiating the self-destruction mechanism may consist of a device operated by projectile set-back force (not shown) and setting means for regulating the duration of the delay (also not shown) may be provided.

The operation of the mechanism is as follows:

Upon target impact, the nose cap 3 is crushed, thereby releasing the tension on the spring 17 which drives firing pin 12 rearwardly to fire the detonator 8. As the pin 12 travels rearwardly, lever 26 rotates counterclockwise to move rounded nose 28 out of its notch 29 whereby release member 20 separates from pin 12.

In event the projectile should miss the target at which it is directed, and the nose cap is not otherwise disturbed, the projectile would become a "dud" and therefore dangerous. In order to prevent this occurrence, the self-destruction mechanism will come into play and destroy the projectile after a predetermined period of time.

The time delay mechanism is preset to operate at a given moment which has been calculated before firing. In operation the gear wheel 35 together with cam 44 will be rotated in a counterclockwise direction on shaft 50 by suitable spring means (not shown) and the release of which is actuated by the set back force of the projectile. Notch 45 in cam 44 will reach a point opposite lug 46 whereby lug 46 will enter notch 45 by the pull of spring 49 on bar 33, freeing bar 33 from locking tab 48 which is engaged by notch 47. Bar 33 will then be moved by further rotation of gear wheel 35 to rotate

21 and the firing pin 12 will fire the detonator 8 by lever 24 and free the rounded nose 28 on lever 26 from notch 29 in release 20. The release 20 will then separate readily due to the beveled walls of notches 19 and action of spring 17.

The speed of gear wheel 35 will be controlled by the gear train 34 and the ratchet 42 and pawl 43.

It will be readily apparent that a highly reliable point detonating and self-destruction mechanism has been devised.

The mechanism is entirely mechanical and will perform under most exacting conditions, especially with rockets travelling at speeds of 5,000 feet per second which present new problems such as instantaneous skin temperatures up to 2,000° F. at the tip of the nose and internal temperatures up to 600° F.

These excessive heats prohibit the use of protechnic, electronic or the like fuze mechanisms even when the fuze mechanisms are insulated from the outer skin of the fuze body.

It is to be understood that the form of the invention, herewith shown and described, is to be taken as a preferred example of the same, and that various changes in the shape, size and arrangements of parts may be resorted to, without departing from the spirit of the invention, or the scope of the subjoined claims.

What is claimed is:

1. In a fuze for attachment to a projectile including a body, a detonating charge in said body, and a hollow nose cap, a point detonating mechanism for said fuze in said body comprising a spring-loaded firing pin slidably mounted in said body and defining a forwardly extending stem portion, said stem being notched at its forward portion thereof, a release member defining a rearwardly notched portion for detachable engagement with said forwardly notched portion on said firing pin, a wire connecting said release member to said hollow nose cap for holding said firing pin in a retracted position and to release said firing pin upon destruction of said nose cap, a self-destruction mechanism adapted to release said firing pin upon failure of the destruction of said nose cap after a predetermined period of time comprising a first lever pivoted at one end in said body, a second lever having a shorter length than said first lever pivoted to the free end of said lever and defining a rounded nose at its free end, said nose adapted to be received in a rounded recess in said release member to retain said firing pin and said release member in engaged relation, a time delay escapement mechanism mounted in said body forwardly of said release member, a circular cam having a circumferential notch adapted to be rotated by said escapement mechanism, a bar pivoted at one end to the free end of said first lever, a lug integral to the free end of said bar and extending under the circumferential surface of said cam and spring means urging said lug towards said circumferential surface of said cam whereby said notch on said cam engages said lug upon rotation of said cam to move said bar and said first lever and displace said second lever to move said nose on said second lever out of said recess in said release member to release said firing pin.

2. In a fuze for attachment to a projectile including a body having a series of coaxial bores therein, a frangible

nose cap attached to said body and a detonating charge in a rearward said bore, a mechanism for the point detonation of said fuze comprising a housing in a said bore forwardly of said detonator, said housing having an axial bore in its rearward portion and a chamber in its forward portion, said chamber being undercut at its forward portion to define a first shoulder in said chamber, a spring-loaded firing member defining a head portion slidable in said bore in said housing, said head defining a firing point integral to its rearward face and an elongated stem portion integral to its forward face, said stem extending a substantial distance in said chamber and provided with a notch in its forward portion thereof, a release member defining a rearwardly notched portion for detachable engagement with said notched forward portion on said stem portion of said firing pin, an insert defining a second shoulder in said chamber, a wire connecting said release member and said nose cap to retain said firing pin in cocked position, said release member adapted to separate from and release said firing pin upon destruction of said nose cap, a first lever pivoted at one end to said insert, a second lever of shorter length than said first lever pivotally connected to the free end of said first lever, said second lever defining a nose at its free end for engagement in a recess in said release member and normally retain said release member and said firing pin stem in engaged position against said first and second shoulders, a supporting structure arranged in a said bore in said body forwardly of said chamber, a time delay escapement mechanism mounted in said supporting structure, a circular cam having a notch in its circumferential surface, said cam being fixed to said escapement mechanism for rotation in a counterclockwise direction thereby, a bar pivotally connected at one end to the free end of said first lever and provided with an integral lug on its free end, said lug extending under the circumferential surface of said cam, there being a notch in the forward portion of said bar, a locking tab carried by said supporting structure for engagement by said notch on said bar to hold said bar against lateral movement and a spring urging said bar towards said cam whereby said lug will be engaged by said notch on said cam upon said counterclockwise rotation to free said bar from said locking tab and move said bar forwardly to rotate said first lever and displace said nose on said second lever from said recess in said release member and free said firing pin.

3. In a device of the character claimed in claim 2 where-in said notch in said firing pin defines a beveled forward wall and said notch in said release member defines a beveled rearward wall, said beveled walls adapted to mate at an angle of 20° to a line perpendicular to the longitudinal axis of said firing pin when said firing pin and said release member are in said engaged relation.
